UNITED STATES PATENT OFFICE.

ALFRED HENRY HOWE, OF NEW YORK, N. Y.

DESIGN FOR A TOWEL-RACK.

44,686.

Specification for Design.

Patented Sept. 23, 1913.

Application filed July 12, 1913. Serial No. 778,777. Term of patent 14 years.

To all whom it may concern:

Be it known that I, ALFRED H. HOWE, a citizen of the United States, and a resident of the city of New York, borough of the Bronx, in the county and State of New York, have invented a new, original, and ornamental Design for a Towel-Rack, of which the following is a specification, reference being had to the accompanying drawing, forming part thereof.

The figure is a perspective view of a towel rack showing my design.

I claim:

The ornamental design for a towel rack, as shown.

ALFRED HENRY HOWE.

Witnesses:

J. H. DROGE,
D. JAEGER.
